UNITED STATES PATENT OFFICE.

CHARLES M. ELLIOTT, OF MISSLER, KANSAS.

DRIVING ATTACHMENT FOR THRASHERS.

Application filed March 24, 1921. Serial No. 455,287.

To all whom it may concern:

Be it known that I, CHARLES M. ELLIOTT, a citizen of the United States, residing at Missler, in the county of Meade and State 5 of Kansas, have invented certain new and useful Improvements in a Driving Attachment for Thrashers; and I do hereby declare the following to be a full, clear, and exact description of the invention, such as 10 will enable others skilled in the art to which it appertains to make and use the same.

The object of the invention is to provide means in the form of an attachment applicable to threshing machines having blowers 15 or blower stackers, whereby the cylinder pulley or the pulley by which motion is communicated from the driving belt to the cylinder is relieved of the load incident to the driving of the blower and whereby an 20 increased purchase of the driving belt upon the cylinder pulley is afforded to minimize the tendency to slipping and lost motion, and whereby the load incident to the driving 25 of the blower is imposed upon a special pulley which, while receiving its motion from the driving belt and hence direct from the motor is not only actuatable without detracting from the efficiency of the cylinder but serves as a means of increasing the driving 30 efficiency of the belt with relation to the cylinder pulley; and with these objects in view the invention consists in a construction and combination of parts of which a preferred embodiment is shown in the drawings 35 inc. wherein:

Figure 1 is a side view of a driving attachment embodying the invention applied in the operation position to a thrasher of which a portion is illustrated showing the 40 relative location of the attachment.

Figure 2 is a rear view of the same.

Figure 3 is a plan view thereof.

Figure 4 is a detail view of the cylinder and power pulleys and showing the relation 45 of the driving belt thereto.

In the construction illustrated, a side beam of the threshing machine, which may be of any preferred type is indicated at 10, with the related supporting means such as 50 the bracket 11 and ground wheel 12, while the adjacent walls of the separator forming a part of the threshing mechanism are indicated at 13 and 14 with the cylinder shaft

15 projecting laterally over the base plate or platform 16 and carrying the usual cylinder pulley 17 which is traversed by the driving belt 18 extending from a suitable motor (not shown).

The device embodying the invention consists of a power pulley 19 disposed in front 60 of the cylinder pulley and in deflecting relation with the lower side or run of the driving belt with the purpose first of increasing the extent of engagement of the belt with the cylinder pulley and of receiving 65 power from the driving belt so as to communicate motion to the blower pulley 20 carried by the shaft 21 which is common to said power pulley 19 and is mounted in bearings 22 and 23 carried by a bracket 70 24 which is mounted upon the base plate or platform 16 to which it may be secured by bolts 25, or equivalent fastening means, and which for securing the necessary rigidity 75 may be braced as indicated at 26.

The blower belt 27 traverses the blower pulley 20 extending forward as in the usual practice to the blower pulley of the stacker (not shown) the tension of the belt 27 obviously being opposed to that of the portion 80 of the driving belt which traverses the power pulley 19, so as to equalize in a measure the strain upon the bracket while insuring primarily the efficient driving of the cylinder pulley and secondly and equally efficient operation of the blower belt, without any possibility of the resistance afforded by the blower mechanism affecting the rotation of the cylinder, and hence without one 85 of the most prevalent disadvantages of the present method of operating the stacker blower.

It will be noted that not only is the driving of the blower accomplished independently of the driving of the cylinder pulley 95 but the efficiency of operation of the latter is increased by the fact that the driving belt is carried approximately around three fourths of the periphery of the cylinder pulley instead of only about one-half of the 100 circumference as in the ordinary practice. The indicated arrangement of the parts moreover serves to maintain an operative relation between the driving belt and the cylinder pulley even without the use of belt 105 tightening means for the reason that the

sagging of the belt, should there be any, serves to increase the frictional contact thereof with the power pulley 19 and hence maintain a proper relation of the belt with 5 the cylinder pulley.

Having thus described the invention, what I claim is:—

1. In a thrasher, the combination with the cylinder pulley and driving belt of a power pulley arranged in deflecting relation with the return run of the driving belt adjacent to the cylinder pulley to increase the bearing contact of the belt with the cylinder pulley, and a blower pulley 10 carried by the shaft of said power pulley for actuating the blower driving belt.
2. The combination with a thrasher blower of a power pulley and blower pulley carried by a common shaft and means for 15 supporting the power pulley in deflecting relation with the driving belt of the cylinder pulley for increasing the wrap of said belt around the cylinder pulley and deriving motion from the belt, said blower pulley being 20 adapted to actuate a blower belt.
3. An attachment for thrasher blowers having a bracket and means for attaching the same to the frame of the thrasher, a power pulley and a blower pulley carried by a 25 common shaft mounted upon said bracket for arrangement with the power pulley in deflecting relation with a run of the driving belt traversing the cylinder pulley and adjacent to the cylinder pulley for increas- 30

ing the extent of wrap of the belt around 35 said pulley.

4. The combination with a thrasher having a cylinder pulley and a driving belt traversing the same, of a blower operating attachment consisting of a power pulley and 40 a blower pulley carried by a common shaft, the power pulley being arranged adjacent to the cylinder pulley in deflecting relation with the driving belt to increase the extent of wrap of said belt around the cylinder 45 pulley, and a blower belt traversing the blower pulley and extending therefrom in the opposite direction from that in which the driving belt extends.

5. In a thrasher, the combination with a cylinder pulley and driving belt of a power pulley arranged to be driven by the driving belt, and a blower pulley operated from said power pulley for actuating the blower driving belt. 50

6. The combination with a thrasher of a power pulley and a blower pulley carried by a common shaft, said power pulley being arranged to be driven by the driving belt of the cylinder pulley and said blower pulley being adapted to drive the blower belt. 55 60

In testimony whereof I affix my signature in presence of two witnesses.

CHARLES M. ELLIOTT.
